MISSILE HANDLING TRAILER

Leo Berner, Pasadena, Calif., assignor, by mesne assignments, to the United States of America as represented by the Secretary of the Navy

Filed May 16, 1962, Ser. No. 196,562
12 Claims. (Cl. 214—501)

This invention relates to a material handling vehicle and more particularly to a new and improved trailer for handling heavy loads such, for example, as a missile or missile components. As is well known, it is common practice in the art of missile handling and launching to store and ship missiles and missile components in individual containers to an ultimate storage depot and/or a launching installation.

Missiles and missile components are made up of extremely delicate tuning, fusing and firing mechanisms and, in many instances, explosively sensitive components which, good safety practice dictates, must be handled with extreme care at all times while maintaining absolute physical control over the unit. Additionally, in many instances such missile and components are of such volume and/or weight as to preclude efficient manual handling thereof. Likewise aerodynamic characteristics of the overall configuration may be of a complexity so as to preclude the use of the normally available hoisting and transporting equipment as used in conventional industrial material handling.

In accordance with the present invention a new and improved cargo or material handling vehicle is provided which particularly well adapted for hoisting, handling and transporting a load of the aforementioned character. More specifically, the present invention provides a handling trailer constructed and arranged to pick up a missile or missile component or stage package from a horizontal position on the ground or from the deck of a railroad flat car or machine tool, transfer the package containing a missile or component, as the case may be, from a horizontal position to a vertical position or for lowering it onto a below ground test stand or below ground into casting pit or onto the trailer for transportation.

It is accordingly an object of the present invention to provide an improved cargo or material handling vehicle which is particularly well adapted for handling and transporting a missile package or load of the afore-mentioned character.

Another object of the invention is the provision of an improved highly maneuverable trailer having hoisting apparatus and stabilizing structure for steadyng the trailer during a handling operation.

A further object of the invention is to provide an improved mobile cargo handling trailer having a simple, light, yet rugged and efficient cargo hoist arrangement thereon as well as load carrying cradles which will receive and support the load during transit, independent of the hoisting arrangement.

A still further object of the invention is the provision of an improved missile trailer constructed and arranged to facilitate the handling and transporting operations incident to the procedures practiced with present day missiles.

It is a further object to provide a new and improved material handling mechanism which overcomes all of the shortcomings of material handling devices heretofore or now in general use while providing all of the desired advantages thereof.

Other objects and many of the attendant advantages of this invention will be readily appreciated as the same becomes better understood by reference to the following

2

detailed description when considered in connection with the accompanying drawings wherein:

FIG. 1 is a side elevational view of the missile trailer constructed and arranged in accordance with the present invention;

FIG. 2 is a plan view of the embodiment of FIG. 1;

FIG. 3 is a rear elevational view of the trailer with the pair of mutually spaced booms thereof in a vertical position;

10 FIG. 4 is an enlarged fragmentary sectional view of one end of the jack screw arrangement for the aforesaid booms;

FIG. 5 is an enlarged fragmentary sectional view of the other end of the jack screw arrangement for the booms;

15 FIG. 6 is an enlarged fragmentary view illustrating the rear saddle and the stop device movable with the booms;

FIG. 7 is a sectional view taken substantially on the line 7—7 of FIG. 6;

20 FIG. 8 is a sectional view taken substantially on the line 8—8 of FIG. 1;

FIG. 9 is an enlarged fragmentary view of the jack screw motor and mounting arrangement therefor;

25 FIG. 10 is a sectional view taken substantially on the line 10—10 of FIG. 9; and

FIG. 11 is a sectional view taken substantially on the line 11—11 of FIG. 6, illustrating the driving connection between the stop device on the booms and the rear saddle member.

30 Referring now to the drawings and more particularly to FIG. 1 therefor, the numeral 10 generally indicates a trailer construction in accordance with the present invention. The trailer comprises a chassis 11 having mutually spaced side rails 12 connected by front and rear platforms 13 and 14, as best shown on FIG. 2. To provide maximum maneuverability of the trailer, the forward end thereof is provided with a single point support 15 connected to the front truck 16 in a conventional manner such, for example, as a universal joint, or the like, the truck including a pair of ground wheels 17 and a draw bar 18, the rear end of the trailer being provided with a pair of equalizer frames 19 pivotally mounted on a transverse axle or shaft 21 carried by the side rails 12. The equalizers 19 are mounted on the shaft 21 for independent rotation and each equalizer has mounted thereon a pair of ground wheels 22, FIGS. 1 and 2.

35 A pair of booms generally indicated by the reference character 23 is carried on the chassis 11, one of each of the pair of booms being disposed adjacent each side rail 12. The booms are carried by a shaft 24 rotatably mounted on the side rails 12 in suitable bearing 25. Each of the booms 23 are of hollow construction and include wide walls 26 connected by top and bottom walls 27 and 28, the bottom wall of each boom having a slot 29 formed therein, as best shown in FIG. 5, the purpose of the slot being hereinafter more fully described. The booms 23 are each provided with a sheave or pulley rotatably mounted at the terminal ends thereof on a shaft 32.

40 Each of the booms are provided with a jack mechanism generally indicated by the reference character 33 and comprising an inner sleeve or support 34 pivotally mounted between a pair of brackets 35, as at 36, carried by each side rail 12. An outer sleeve 37 is disposed about the inner sleeve or support 34 and has secured thereto, as by bolts 38, a sleeve nut or actuating element 39. The sleeve 37 and sleeve nut 39 having a sprocket 41 disposed therebetween and secured thereto by the aforesaid bolts 38, the sleeve 37 and sleeve nut 39 being rotatably supported on the support 34, as by roller bearings, or the like, 42. The jack mechanism further includes a jack screw 43 in threaded engagement with the sleeve

nut 39, the jack screw extending through the aforesaid slot 29 in bottom wall 28 of the boom and pivotally mounted between the side wall 26 thereof as at 44. By the aforesaid arrangement and upon rotation of the sleeve nuts 39, the jack screws associated with each boom are adapted to move the booms to a desired position such, for example, as the various positions shown in dashed outline, FIG. 1.

To facilitate rotation of the sleeve nuts 39 of each jack mechanism an electric motor 45 is mounted on a bracket or support 46, the motor being provided with a sprocket 47. A sprocket chain 48 provides a driving connection between the sprocket 47 on the motor and sprocket 41 on each of the sleeve nuts 39, as best shown on FIG. 8. The support 46 is provided at each end thereof with a bearing 49 for receiving and allowing free rotation of the sleeve nut of each jack mechanism, FIG. 10.

A stop device or member generally indicated by the numeral 51 is carried by the shaft 24 and includes a pair of mutually spaced hubs 52 secured to the shaft 24 in any conventional manner, and a platform 53 extending therefrom and terminating in a lip or stop member 54, disposed at a right angle with respect to the platform. The stop device is secured to the shaft 24 so that it moves in unison and concurrently with the booms. The shaft 24 further supports a rear saddle 55, the saddle being disposed between the hubs 52 of the stop device 51 and rotatably mounted on the cylindrical portion 56 of the shaft 24 so that the saddle 55 rotates on the shaft a predetermined amount and independently of the twin booms 23 during an initial hoisting operation such, for example, as when the booms 23 are in position 2 and the missile container C is hoisted from the aforesaid saddles 55 and 71, FIG. 1.

The hoisting arrangement for the container C includes a pair of synchronized electrical motors 57 mounted on the platform 13, one for each boom, as best shown on FIG. 2. Each motor is provided with a gear box 58 containing conventional gear arrangements in driving connection with a cable drum 59 for imparting rotation thereto. The drums 59 each carry a hoisting cable 61 trained over the pulley 31 at the terminal end of each boom 23 and over a complementary pulley 62 disposed on opposite sides of the container C and thereafter secured to their respective pulleys 31. The pulleys 62 are carried by a split band 63 or harness disposed about the container C and secured thereto by a bolt and ear or lug arrangement, as at 64, as best shown on FIGS. 2 and 3.

The trailer is further provided with an arrangement for controlling the horizontal or partially inclined position of the container after the container has been hoisted from the aforesaid saddles. This arrangement includes an electric motor 65 mounted on the platform 14 and having gear box 66 containing conventional gear arrangement in driving connection with a cable drum 67 carrying a control cable 68 and having the free end thereof connected to an eye 69 secured to the front end of the container C.

The rear saddle 55 cooperates with a front saddle 71 carried by the side rails 12 for receiving and supporting the container C during transportation, as best shown on FIG. 1. It will be further noted in FIG. 1 that when the container is in a position for transportation the lip 54 on the stop device 51 engages the rear end of the loaded container C and a chain or cable secured to eye 69 and connected to a similar eye 73 carried by the chassis, maintains the loaded container in this position.

A forward substantially U-shaped outrigger or supporting device 74 comprising a surface engaging element 75 and a pair of mutually spaced arms 76 is mounted on the chassis, each arm being secured to and rotatable with one of each of the shafts 36, FIGS. 1 and 4. A similar substantially U-shaped outrigger of supporting device 77 is mounted at the rear end of the chassis and comprises a surface engaging element 70 having an arm 79 dis-

posed at each terminal end thereof, the arms being carried and movable with shaft 81 rotatably mounted in extensions 82 formed at the rear end of each side rail 12, FIGS. 2 and 3.

To actuate the outriggers 74 and 75 into and out of engagement with a surface, a shaft 80 is mounted on one of the side rails 12, as by bearings 80', the shaft being provided at one end with a worm 84 in driving engagement with a worm wheel 85 secured to one of the shafts 36, the shaft 80 being further provided at the other end thereof with a worm 86 in driving engagement with a worm wheel 87 secured to the shaft 80. A crank 88 or other suitable means may be provided for actuating the shaft 80 so that the aforesaid outriggers 74 and 77 may be moved from an initial position to an operating position thereby to maintain the trailer or vehicle in a stabilized condition and to lock the trailer to the surface of a floor or ground, as the case may be, during necessary operational procedures.

As best shown on FIGS. 6 and 7, the hubs 52 of the stop member 51 each carry a pin or detent 89 disposed with a complementary slot 91 formed in the rear saddle 55 to facilitate free rotation of the saddle on the portion 56 of the shaft 24 so that it can move with the container C and independent of the twin booms a predetermined amount. For example, when the booms are in the dashed line position 2, FIG. 1, and the container is hoisted by the hoisting cable 61 and hoisting motors 57, the lighter forward end of the container due to the fact that the harness and sleeves thereon are disposed forwardly of the center of gravity of the container causes the lighter forward end of the container to be lifted from the front saddle while the heavier rear end thereof remains on the rear saddle. Thus, by reason of the aforesaid slot and pin arrangement the rear saddle will rotate independently of the booms a predetermined amount. However, upon further movement of the booms away from position 2 and by reason of the slot and pin arrangement the rear saddle will rotate with the booms. It will be further understood that after complete over head suspension of the container has been accomplished, the aforesaid control motor 65 and cable 68 secured to the eye 69 at the forward end of the container, controls the horizontal or partially inclined positions of the suspended load. Furthermore, to limit the load on the jack screws 43 of the jack mechanism 33 and to hoist the load with efficient tackle position, the twin booms will only be loaded between positions 2 and 4, FIG. 1, position 1 being the transporting or traveling position for maximum overhead clearance, with the booms resting on the front saddle 71 and the container C resting on saddles 55 and 71. The booms are adapted to rotate in an empty condition from positions 1 to 2 and raise or lower the load in position 2.

The aforesaid twin boom arrangement permits the passage of the load between the booms for complete freedom for handling the load into any position from horizontal to vertical and vice versa. Moreover, by the aforesaid arrangement loads can be hoisted relatively high to be set vertically on a stand well above ground or it can be lowered below the ground into a pit or the like. By booming far out beyond the rear end of the chassis to position 4 and by utilizing the control cable 68, the load may be picked up from or lowered into a horizontal position, above or below the ground by always maintaining the outer heavy end low. At the low light end position the control cable 68 becomes ineffective. In these positions, therefore, control is accomplished by the hoisting tackle as long as ground contact is maintained on the heavy end of the load and until the light end of the load is high enough for control by the control cable 68.

As illustrated, the jack mechanisms 33 serve to position the twin booms, which handle the load by means of sheaves 31 at the boom ends and lower sheaves 62 on container harness 63. Power to the sheaves is provided

by the aforesaid electric motors 57 and winch arrangements 59 mounted at the forward end of the trailer chassis 11 and these units also serve as counterweights for the extreme backward position of the booms. If so desired, an additional permanent counterweight may be located in a box or container 92 mounted at the forward end of the chassis 11, FIG. 1, the counterweight being used during a loading and unloading operation and may be removed to reduce the transport weight.

A further feature of the trailer design is that its initial cost is extremely low, which is accomplished first by not making the vehicle self-propelled, but by moving it by means of any conventional prime mover and secondly by eliminating a costly independent power source on the chassis to operate the hoisting and control winches and the two screw jack mechanisms which manipulate the twin boom positions. The aforesaid winches and screw jack mechanisms are powered by simple and inexpensive electric motors, the motors being provided with suitable electrical cables 93 connected to an electrical socket 94, thereby to provide an external electrical connection for the motors. If desired, however, the trailer may be provided with a small power panel, accessible from the ground for control of the individual motors, either direct or from pendant controls.

Obviously many modifications and variations of the present invention are possible in the light of the above teachings. It is, therefore, to be understood that within the scope of the appended claims the invention may be practiced otherwise than as specifically described.

What is claimed is:

1. A load carrying and handling trailer comprising a rectangular chassis, a plurality of ground wheels attached to and supporting said chassis, load receiving and supporting means mounted on said chassis, stabilizing means mounted on said chassis for interconnecting the chassis with the ground, means operatively connected to said stabilizing means for actuating the stabilizing means from an initial position to an operating position, a pair of mutually spaced booms rotatably mounted on the chassis, said booms being spaced so as to accommodate the load therebetween, jack means supported on the chassis and connected to said booms for operating the booms, operating means for said jack means, load hoisting means supported on the chassis and cooperating with each of the booms, pulley means carried by each of the booms, complementary pulley means attached to the load, a first working cable operated by said hoisting means and interconnecting the pulley means on the booms and the load for hoisting the load from said receiving and supporting means, load control means supported on the chassis, a second working cable operated by said load control means for controlling the inclination of the load when the load has been hoisted from the receiving and supporting means, and stop means rotatably mounted on the chassis and movable in unison with the pair of booms for maintaining the load on the receiving and supporting means during a load transporting operation.

2. A load carrying and handling trailer according to claim 1, wherein said stabilizing means includes a forward and rear substantially U-shaped outrigger having ground engaging devices carried thereby.

3. A load carrying and handling trailer according to claim 1, wherein said load receiving and supporting means includes a front saddle fixed to said chassis and a rear saddle mounted on the chassis for rotation with the load a predetermined amount during a hoisting operation.

4. A load carrying and handling trailer according to claim 1, wherein said stabilizing actuating means includes a shaft mounted on said chassis and having a worm at each end thereof in driving connection with the stabilizing means for moving the stabilizing means from said initial position to said operating position.

5. A load carrying and handling trailer according to claim 1, wherein said jack means includes a pair of jack sleeves rotatably supported on the chassis, a jack screw in threaded engagement with each of the jack sleeves and pivotally connected to each of the booms, and a supporting sleeve pivotally mounted on the chassis and disposed within each jack sleeve for rotatably supporting each sleeve.

6. A load carrying and handling trailer according to claim 1, wherein said operating means includes a motor in driving connection with the jack means.

7. A load carrying and handling trailer according to claim 1, wherein said load hoisting means includes a pair of motors and a cable drum for each motor of said pair of motors and for each boom of said pair of booms.

8. A load carrying and handling trailer according to claim 1, wherein said load control means includes a motor and a cable drum.

9. A load carrying and handling trailer according to claim 1, wherein said stop means includes a platform having a pair of mutually spaced mounting hubs at one end and a load engaging element at the other end thereof.

10. A load transporting and handling trailer comprising a rectangular chassis, a plurality of ground wheels attached to and supporting said chassis, load receiving and supporting means mounted on said chassis, said receiving and supporting means including a fixed front saddle and a rotatable rear saddle, rotatably mounted front and rear stabilizing devices mounted on the chassis for interconnecting the chassis with the ground, means including a drive shaft in driving connection with said stabilizing devices for actuating said stabilizing devices, a pair of mutually spaced booms rotatably mounted on the chassis, jack mechanisms pivotally connected to the chassis and to each of said booms for operating said booms, means operatively connected to each of said jack mechanisms for actuating the mechanisms, a hoisting winch supported on the chassis and cooperating with each of the booms, complementary pulley means attached to the load and positioned forwardly of the center of gravity of the load, a first working cable operated by said hoisting winch and interconnecting the pulley means on the booms and the pulley means on the load for hoisting the load from said front and rear saddles, a load control winch supported on

20 the chassis, a second working cable operated by the load control winch and attached to the forward end of the load for controlling the position of the load after the load has been hoisted from the front and rear saddles, stop means rotatably mounted on the chassis and movable in unison

25 with the booms, and a stop element carried by said stop means in engagement with one end of the load for preventing accidental displacement of the load during a load transporting operation.

11. A load carrying and handling trailer according to claim 10, wherein said jack mechanisms include a pair of supports pivotally mounted on the chassis, a rotatable sleeve carried by each of said supports, and a jack screw in threaded engagement with each of said sleeves pivotally connected to each of the booms.

12. A load carrying and handling trailer according to claim 10, wherein said operating means includes a sprocket carried by each of the sleeves, a motor mounted on the chassis and having a driving sprocket carried thereby, and a sprocket chain interconnecting the sprockets on the sleeves and the motor.
